UNITED STATES PATENT OFFICE.

MARTIN P. TORGRUD, OF WHALAN, MINNESOTA.

GATE-FASTENER.

1,106,324.

Specification of Letters Patent.

Patented Aug. 4, 1914.

Application filed May 13, 1910. Serial No. 561,125.

To all whom it may concern:

Be it known that I, MARTIN P. TORGRUD, a citizen of the United States, residing at Whalan, in the county of Fillmore and State 5 of Minnesota, have invented certain new and useful Improvements in Gate-Fasteners, of which the following is a specification.

My invention relates to an improvement in an attachment to be applied, preferably, 10 to frameless gates, and the object is to provide means whereby the gate can be locked in position. In gates which are formed from wire, it is necessary to provide means which will cause the wire to be stretched 15 sufficiently to hold it sufficiently taut.

The invention consists in certain novel features of construction and combinations of parts which will be hereinafter fully described and pointed out in the claim.

20 In the accompanying drawings:—Figure 1 is a view in elevation, showing the fastener applied to a gate in locked position; Fig. 2 is a similar view, showing the gate released; and Figs. 3 and 4 are detail views 25 of the fastening means.

A and A' represent the fence posts. Connected to the post A' are the wire strands 1, which strands are connected to the stile 2. A bar 3 is connected to the strands 1 at the 30 central portion of the gate, for holding the strands in proper position. A link 4 is connected to the base of the post A, in which one end of the stile is received in closing and locking the gate.

35 Mounted upon the post A is an angular bracket 5. The upper portion of the bracket is provided with a bifurcated or forked end 6, in which is pivotally mounted a lever 7. The U-shaped clasp 8 is connected to the 40 bracket 5, and is provided with spring arms 9 and 10. The arm 10 is provided with a lug 11 which is adapted to engage the upper surface of the lever 7 for holding it in locked position between the arms. A loop 45 12 is connected to the lever, which is adapted to be received over the upper end of the stile 2, which is held in position by a lug 13 on the stile.

In closing the gate, the lower end of the stile is inserted in the link 4, and the loop 50 12 on the lever 7 is placed over the upper end of the stile, then the lever 7 is thrown or drawn over between the arms 9 and 10, and forced downward until the upper surface of the lever is engaged by the lug 11, 55 whereby the gate is held in closed position.

To release the gate, the lever 7 is released from the clasp by drawing the arm 10 outward to disengage the lever from the lug 11. After the lever has been released, the 60 loop 12 can be removed from the stile, and the stile can then be disconnected from the link 4, when the gate can be swung open.

Having fully described my invention, what I claim as new and desire to secure by 65 Letters Patent, is:—

The combination with a frameless gate provided with a stile, a post, of a bracket secured to the top of the post having a bifurcated or forked upper end, a lever 70 pivotally connected to the forked end of the bracket, a loop pivotally connected with the lever and adapted to engage with the upper end of the stile, a U-shaped clasp mounted on the angular bracket and provided with 75 vertical parallel spring arms between which the lever is received, a lug mounted on one of the arms projecting toward the other arm, said lever engaging the lug and one arm when swung to a horizontal position for 80 causing the arms to be forced apart to permit the lever to pass below the lug whereby the lever will be held in a horizontal position and against the lateral movement, the lug carrying arm being of greater length 85 than the other arm, so that sufficient leverage can be obtained for drawing it away from the opposite arm to allow the lever to be withdrawn from between the arms.

In testimony whereof I affix my signature, 90 in the presence of two witnesses.

MARTIN P. TORGRUD.
